UNITED STATES PATENT OFFICE.

GUSTAF AKERLUND, OF ATLANTA, GEORGIA, ASSIGNOR TO STANDARD GAS POWER COMPANY, OF ATLANTA, GEORGIA, A CORPORATION OF GEORGIA.

GAS-GENERATOR.

1,115,268.

Specification of Letters Patent. Patented Oct. 27, 1914.

Application filed February 2, 1912. Serial No. 675,008.

To all whom it may concern:

Be it known that I, GUSTAF AKERLUND, a subject of the King of Sweden, residing at Atlanta, county of Fulton, and State of Georgia, have invented certain new and useful Improvements in Gas-Generators, of which the following is a specification.

This invention relates to gas generators.

The present invention relates to those gas generators which are intended to generate or produce gas which is intended to be subsequently cooled, cleaned and purified by suitable means to condition it for consumption by a gas engine or for power purposes.

15 It is generally admitted that a single zone suction down draft gas generator or producer is the simplest and easiest to operate, but heretofore difficulty has been experienced in this type of generator on account of there being no provision for the supply of air to all parts of the fire and consequently some of the coal passes through to the ashes in the form of coke, thus materially reducing the efficiency of the producer.

20 The present invention has for its object the provision of a gas generator or producer having means for admitting air to all parts of the fire in a manner without interfering with the uniform direction of the draft, thereby insuring complete and thorough combustion and extraction of all of the gas from the fuel so that all of the fuel is eventually converted into ashes.

25 The foregoing object is accomplished by the provision of means for introducing secondary air into and throughout the fire below the upper zone of the fuel and through the coke zone and, further, to introduce secondary air in the foregoing manner in connection with a central gas off-take which, in the down draft generator or producer type of the present invention, is located at the lower part thereof.

30 In carrying out that part of the invention which contemplates the introduction of the secondary air to the fuel, I provide means for combining vapor with the air so that both are introduced into the fire.

35 A generator or producer provided with the central gas off-take of the present invention may, for convenience and economy of use be also provided with a side gas off-take, but I wish it understood that I do not consider the side off-take as necessarily combined with the center off-take, although in

the present invention a new arrangement of ducts or pipes and valves may be employed whereby, if both side and center gas off-takes be provided, one or the other may be cut off from the point of delivery of the gas 60 from the generator as may be required.

The invention is not limited to the specific central gas off-take shown in the drawings and hereinafter set forth, that feature of the invention residing in the provision of a 65 gas off-take which will receive the gas substantially centrally of the ash zone of the producer.

In carrying out the various features of the invention, modifications of structure may be 70 resorted to without departing from the mode of operation and the constructions set forth hereinafter and shown in the accompanying drawings are to be considered as illustrative, rather than restrictive, of the invention.

75 In the accompanying drawings:—Figure 1 is a vertical section; Fig. 2, a plan; Fig. 3, a face view of a certain valve; and Fig. 4, a horizontal section through a certain twyer.

80 The generator is preferably supported on a suitable concrete or other foundation 1, in which is a water pit 2 preferably of circular form, and rising centrally thereof is a substantially conical ash pier 3. The generator 85 is supported on pillars 4, the lower metallic part 5 of the generator, which is in the form of a shell, being immersed in the water in the pit 2 so that it is always protected against the heat and the seal is sufficiently 90 deep to prevent the exhaust or suction which may be used in connection with the generator or the system in which it is used, from breaking the seal at this point.

95 The generator has a filling opening 6, poke holes 7 and any other or necessary adjuncts, aside from the inventions which it embodies and which are set forth hereinafter.

100 In the lower part of the generator there is a tapering shell 8 which is surrounded by circular shell 9, the two constituting the walls of the vaporizer 10, containing water which may be supplied in any suitable manner.

105 The side gas off-take is shown at 11. Air is introduced into the space above the water in the lower or primary vaporizer 10 through one or more induction pipes 12 embedded in the brick work of the producer and the air entering these pipes is pre- 110

- heated by the heat from the fire before reaching the vaporizer; the pre-heated air mixes with the vapor rising from the water and arises through one or more pipes 13 which communicate with the mixture in-take pipes 14 for directing the mixture of vapor and air into the generator. To control and regulate the discharge of the mixture, there is provided an adjustable valve 15.
- 10 The stack is shown at 16 and through it waste gases may vent when the generator is idle or when the draft is reversed therethrough in the manner set forth in my Patent No. 992,840, May 23, 1911.
- 15 An over-flow 17 is provided for the vaporizer 10 whereby the level of the water may be kept constant.
- As thus far described, the generator is generally set forth in my earlier Patents 20 925,415, June 15, 1909, and 992,840, May 23, 1911.
- 25 Disposed at the lower part of the generator or producer at the center thereof, is the gas off-take 18 which preferably extends down through the conical pier 3 and is preferably provided with a guard or hood. 19 which, by preference, is of conical form so that the ashes will readily gravitate thereover without having access to the off-take 30 18. The off-take 18 communicates with an inclined drain and duct 20 which is provided with a draining valve 21, the end of the duct 20 being preferably received in a dry pit 22 in the concrete foundation 1, so that the impurities separated from the gas may be drawn off into the pit 22. To separate the impurities carried by the gas, one or more water sprinklers 23 are provided which, by cooling and spraying the gas, cause it to give up some of its heavy impurities. The sprinkler or sprinklers 23 are controlled by a valve 24 and the water supply may be derived from any suitable source.
- 35 Rising from the duct 20 is a pipe 25. The gas may be taken from the pipe 25 to any suitable point, but is preferably passed from said pipe through suitable cleaning means which will cool and clean it of its impurities.
- 40 I wish it understood that in the present invention the side off-take 11 is not essential, certainly not as combined with the center off-take 18, but to enable the gas to be drawn from either the center or side of the generator, means may be provided, such as now will be set forth, whereby the number of pipes and valves may be minimized and yet control of both the side and center off-takes insured. To that end the leg or pipe 25 is 45 entered into a coupling 26 which in turn is in communication with a coupling 27, and that in turn is connected by a pipe with the off-take 11. Valves 28 and 29 provide for establishing or closing communication between the off-take 11 and the coupling 27

on the one hand, and between the off-take 18 and said coupling 27. When the off-take 18 is to be used, the valve 28 will be closed and valve 29 open; when off-take 11 is to be used, the valve 28 will be opened and the valve 29 closed. From the coupling 27 the gas may be taken to any point as, for instance, to the cooler of the gas producer system with which the generator is used. In carrying out my invention, however, the take-off 11 may be entirely dispensed with and the gas may be taken from the off-take 18 in any desired manner.

The gas may be taken off substantially centrally of the ash zone in any manner, the purpose of the invention being to provide means for taking off the gas at this point, in connection with the delivery of a draft directly into the heated body of the fuel at a plurality of points so that the draft converges toward the gas off-take.

Surmounting the generator is a secondary vaporizer 30 which may receive its water supply through any suitable pipe 31 having a controlling valve 32 by which water may be admitted thereto as desired. The air inlet pipes 12 pass down through the secondary vaporizer 30, but have no communication therewith.

Air is admitted to the secondary vaporizer 33, such supply being controlled by a valve 34. Communicating with the pipe 33 is pipe 35 which leads to the space above the water in the primary vaporizer 10. A valve 36 controls pipe 35.

When the valve 36 is closed and valve 34 is opened, air will be admitted to the secondary vaporizer 30. On closing the valve 34 and opening the valve 36, the surplus vapor and steam from the vaporizer 30 will pass into the primary vaporizer 10 and mingle with the vapor therein to augment it so that the mixture rising through pipe 13 may thus be augmented for the purpose of additional treatment of the fire when 110 desirable or necessary.

Opening into the interior of the generator or producer, through the walls thereof, are the secondary air and steam twyrs 37. These twyrs are disposed below the fuel zone A and at or about the top of the coke zone B which in turn is above the ash zone C. Heretofore in down draft suction gas generators or producers, a certain amount of the fuel in the upper part thereof has undergone only an imperfect combustion and passed through into the ashes in the form of coke due to the imperfect distribution of the air and vapor, either or both. My invention remedies this defect and insures practically perfect gasification of the fuel. This is due, first, to the provision of the twyrs or air, steam and vapor inlets 37; second, to the provision of the central gas off-take 18; and thirdly, to the conjoint 130

use or combination of these twyers and the central off-take. The twyers admit the air, vapor and steam at numerous points in a ring or at about the same level in the fire 5 below the fuel zone and substantially at the top of the coke zone B and the down draft toward the gas off-take 18 causes numerous streams of air, vapor and steam to pass through the fire uniformly, resulting in a 10 practically perfect combustion and insuring that only ashes will pass into the pit 2, thereby obviating the very considerable loss of fuel and decrease of efficiency which has heretofore prevailed.

15 The twyers 37 are connected by air, vapor and steam pipes 38 with the upper or secondary vaporizer 30 and the supply of air, steam and vapor is controlled by suitable valves. Preferably, the twyers are arranged 20 in sets and each set has its own pipe connection 38 and own valve 39, so that the supply of the steam air, and vapor from the secondary vaporizer 30 may be regulated for sections of the generator or producer.

25 Furthermore, each twyer may have a valve 40 so that one or more of the twyers of any set may be cut off if desired.

The primary vapor, steam and air mixture, subject to control by the valve or 30 valves 15, is taken from the lower vaporizer 10 and admitted through the in-take 14 as I have proposed to do in my earlier patents. The secondary supply of air, vapor and 35 steam is taken from the secondary vaporizer 30 and, suitably distributed and regulated as may be desired by the valves 39 and 40, is admitted to the fire below the upper zone and substantially at the upper part of the coke zone and due to this and the provision of the center gas off-take 18, the air, 40 steam and vapor are uniformly distributed throughout all parts of the fire, resulting

in a practically perfect combustion and very great increase in efficiency.

Having thus described my invention, what 45 I claim as new and desire to secure by Letters Patent, is:—

1. In a down-draft generator adapted to maintain a lower ash zone, an upper fuel zone and an intermediate fire zone, means 50 positioned and adapted for delivering a draft directly into the heated body of the fuel in the fire zone at a plurality of points of the outer part of said fire zone, in combination with a gas off-take arranged so 55 that it will receive the gas substantially centrally of the ash zone, whereby the downward draft is caused to uniformly traverse all parts of said fire zone in a direction toward the receiving portion of the gas off- 60 take.

2. In a down-draft generator adapted to maintain a lower ash zone, an upper fuel zone and an intermediate fire zone, means positioned and adapted for delivering a 65 draft directly into the heated body of the fuel in the fire zone at a plurality of points of the outer part of said fire zone, in combination with a gas off-take arranged so that it will receive the gas substantially 70 centrally of the ash zone, whereby the downward draft is caused to uniformly traverse all parts of said fire zone in a direction toward the receiving portion of the gas off- 75 take, and means for admitting an independent primary draft into the upper part of the generator in the region of the fuel zone.

In testimony whereof, I hereunto affix my signature in presence of two witnesses.

GUSTAF AKERLUND.
